(57) **CLAIM**

The ornamental design for a portion of a front panel, substantially as shown and described.

DESCRIPTION

The ornamental design of the present invention is for a front panel and portion of a front panel for a signal processing device, such as an audio or video signal processing device, a signal measuring device, or the like.

FIG. 1 is an upper left front perspective view of a first portion of a front panel showing my new design.

FIG. 2 is a front elevational view of a first portion of a front panel showing my new design.

FIG. 3 is a top plan view of a first portion of a front panel showing my new design.

FIG. 4 is a bottom plan view of a first portion of a front panel showing my new design.

FIG. 5 is a right side elevational view of a first portion of a front panel showing my new design; and,

FIG. 6 is a left side elevational view of a first portion of a front panel showing my new design.

The broken line showing in the claimed area of the device of FIGS. 1-6 is for illustrative purposes only and forms no part of the claimed design.
